UNITED STATES PATENT OFFICE

SAMUEL SHAFER, JR., OF MILWAUKEE, WISCONSIN, ASSIGNOR TO CHAIN BELT COMPANY, OF MILWAUKEE, WISCONSIN, A CORPORATION OF WISCONSIN

VIBRATING SKIP FOR CONCRETE MIXERS

Application filed January 11, 1929. Serial No. 331,911.

This invention relates to concrete mixers and more particularly to that type of mixer which comprises a rotatable drum which is adapted to be charged with aggregates by means of a pivoted skip and has for one of its objects to provide a simple and effective means whereby such loading skip may be agitated or vibrated when in its discharging position to assist in the movement of the aggregates from the skip into the drum. 5

A further object of the invention is to provide a skip vibrating means which will be simple in construction, comparatively inexpensive to manufacture and more efficient in use than those which have been heretofore proposed. 15

A still further object of the invention is to provide a skip vibrating means in which the skip will be vibrated only during the time it 20 is in its discharging position, such vibration being accomplished through the rotary movement of the mixing drum.

With the above and other objects in view which will appear as the description proceeds, 25 the invention consists in the novel details of construction and combinations of parts more fully hereinafter described and particularly pointed out in the appended claims.

Referring to the accompanying drawings 30 forming a part of this specification in which like reference characters designate like parts in all the views:

Fig. 1 is a front elevational view of a concrete mixer of well known form with the present invention applied thereto. 35

Fig. 2 is a side elevational view of the parts shown in Fig. 1, and

Figs. 3 and 4 are enlarged fragmentary sectional elevational views showing in detail the 40 different positions assumed by the parts in the operation of the invention.

Referring more particularly to the said drawings there is shown a concrete mixer having a frame 10 in which is rotatably mounted a mixing drum 11 which is driven by an internal combustion engine or other prime mover 12 in the usual manner. The mixer is also provided with a loading skip 13, the forward portion of which is provided 45 with a saddle 14 which is pivotally carried on

a shaft 15. The ends of the said shaft 15 are received in bearing members 16, which, as will be clear from Figs. 2, 3 and 4, are elongated, and are pivoted as at 17 to the frame 10. As will be clear from the drawings, the 55 pivots 17 are disposed in a plane above the shaft 15, and the said members 16 as well as the shaft 15 are therefore pendently mounted.

The skip 13 is provided at its sides with rollers or projections 18, which are adapted 60 to engage with cams or lugs 19 formed upon or secured to the drip ring 20 of the mixing drum 11. Obviously the rollers 18 will only contact with the cams or lugs 19 when the skip is in its raised or discharging position 65 indicated in dotted lines in Fig. 1.

The lower ends of the bearing members 16 are preferably enlarged as indicated at 21, and form heads which normally engage against the longitudinal frame member 22 to 70 limit the pendent movement of the member 16 in one direction.

The operation of the device will be clear from the foregoing, but may be briefly summarized as follows: 75

When the skip bearing the charge of aggregates is raised from its full line position in Fig. 1 to its dotted line position, the rollers 18 will be brought into engagement with the flat face of the drip ring 20 of the mixing 80 drum 11. Inasmuch as this drum is constantly rotated during the operation of the machine, the lugs or cams 19 will be brought into engagement with the rollers 18, thereby tending to force the said rollers and the skip 13 85 away from the drum. This movement is permitted through the pendent mounting of the skip and shaft 15 on the pivots 17, and of course as the rollers ride up the inclined face of the cams 19 the parts will assume the positions shown in Fig. 4. As the cams 19 pass from beneath the rollers, due to the continued rotation of the drum, the pendent mounting of the skip will cause the parts to drop back to the position shown in Fig. 3, with the result that when the head 21 of the bearing members 16 strikes the frame member 22 the skip will be jarred, thereby facilitating the discharge of aggregates into the drum. 95

While only two cams or lugs 19 have been 100

shown upon the drip ring 20, obviously a greater number may be employed so as to cause a greater number of vibrations for each rotation of the drum.

5 While one form of the invention has been illustrated and described it is obvious that those skilled in the art may vary the details of construction as well as the arrangement of parts without departing from the spirit of 10 the invention, and therefore it is not wished to be limited to the above disclosure except as may be required by the claims.

What is claimed is:

13 1. In a concrete mixer, a rotatable mixing drum; a pivoted charging skip, movable from a load-receiving position to a load-discharging position in proximity to said drum; and means operable from said drum for vibrating said skip when in said load discharging position.

20 2. In a concrete mixer having a mixing drum and a pivoted charging skip therefor, a pendent mounting for said skip; and means operable from said mixing drum for swinging 25 said skip on its pendent mounting to facilitate the discharge of materials from said skip into said drum.

30 3. In a concrete mixer, a rotatable mixing drum provided with a projection; a charging skip for said drum, pivotally and pendently mounted relative thereto; and means carried by said skip adapted to coact with said projection as said drum is rotated to move said skip on its pendent mounting.

35 4. In a concrete mixer, a rotatable mixing drum having a drip ring; a plurality of projections carried by said drip ring; a charging skip for said drum, pivotally and pendently mounted relative thereto; and rollers carried by said skip adapted to be brought 40 into the path of said projections when the skip is swung on its pivotal mounting to discharge position, whereby movement may be imparted to said skip on its pendent mounting.

45 5. In a concrete mixer, a frame; a mixing drum rotatably mounted in said frame, provided with a plurality of cam surfaces; a pair of bearing members pendently mounted on 50 said frame; a charging skip for said drum pivotally carried by said pendent bearing members; and members carried by said skip adapted to be brought into co-operative relation to said cam surfaces when the skip is 55 raised to discharging position, whereby movement may be imparted to the skip and bearing members.

60 6. In a concrete mixer, a frame; a mixing drum rotatably mounted in said frame, provided with a plurality of cam surfaces; a pair 65 of bearing members pendently mounted on said frame; a charging skip for said drum pivotally carried by said pendent bearing members; and members carried by said skip adapted to be brought into co-operative rela-

tion to said cam surfaces when the skip is raised to discharging position, whereby movement may be imparted to the skip and bearing members, the free ends of said bearing members engaging a portion of said frame to limit movement thereof in one direction.

70 In testimony whereof I affix my signature.
